UNITED STATES PATENT OFFICE.

SEYMOUR SUITS, OF PHILADELPHIA, PENNSYLVANIA.

REFLECTOR FOR HEADLIGHTS.

Application filed May 15, 1928. Serial No. 277,873.

This invention relates to a reflector for headlights.

The object of the invention is to provide an improved headlight reflector.

Another object of the invention is to provide a reflector which may be conveniently and economically manufactured.

Still another object of the invention is to provide a reflector constructed from a single piece of material and so formed that the rays emanating therefrom will not be reflected upwardly so as to cause glare, but will be directed downwardly, forwardly and outwardly at the points required to be illuminated.

According to the invention, the reflector is paraboloidal in shape with provision for a light source, one part of the reflector, without change of contour, being pressed out from a point near the center of said reflector and extended so as to assume a position at a point near its periphery slightly in advance of the position which it normally would have so that the rays of light from the reflector are reflected downwardly, forwardly and outwardly.

The drawings illustrate an embodiment of the invention and the views therein are as follows:

Figure 1 is a side view partly in vertical section and shows the position of the lamp and its reflective relation to the reflector faces,

Figure 2 is a front view of a headlight with a portion of the rim and lens broken away in order to illustrate the shape of the pressed out portion of the reflector,

Figure 3 is a fragmentary vertical section and may be assumed to be taken on the line 3—3 of Figure 2,

Figure 4 is a fragmentary rear view of a slightly modified arrangement of the pressed out portion and may be assumed to be taken looking in the direction of the arrow in Figure 3.

As illustrated in the drawings, a headlight which has a casing 5 is shown to illustrate the manner in which the reflector 6 is mounted and the usual lens 7 which is secured in place in the casing by the rim 8. A socket 9 for the reception of an incandescent light bulb 11 of any conventional type is mounted in the casing in the usual manner and the socket contains the usual contacts which are electrically connected to any suitable source of

electric current (not shown). The filament 12 of the electric bulb 11 is approximately at the focal point of the reflector.

The invention herein consists in the reflector and method of constructing the same.

As illustrated in Figure 3, the paraboloidal reflector is cut along the arcuate concentric line 13 and from the ends of this arcuate cut it is cut along the curved lines 14 and 16 to the points 17 and 19 near the periphery of the reflector.

Without then changing the original shape of that part of the reflector included between the lines 13, 14 and 16, so that its contour remains unchanged, the same is pressed outwardly, as shown in Figure 1, so that the upper end thereof extends outwardly from the main body 6 of the reflector and the distance from the position formerly occupied by the pressed out portion gradually decreases downwardly so that the point where the same contacts with the lens 7, designated by the numeral 21, will be slightly above its original unraised position. This in effect produces a paraboloidal reflector with a section thereof standing outward therefrom and which, while retaining its shape as part of the paraboloid, will have changed its relation with the focal point 12 for the light bulb 11.

In order that the description may be more readily understood, let us now consider the pressed out portion which I will designate as 22, as the sub-reflector.

In Figure 1, the focal point of the reflector 6 is at the intersection of lines 23 and 24 so that a ray of light emanating from the focus will strike the reflector 6 at the point 26 and be reflected horizontally, as shown by the line 27.

For the purpose of illustration, the filament has been shown as having its rear edge in the focus and extending forwardly therefrom so that a ray of light 28 emanating from the tip of the filament would strike the reflector at the point 29 and be reflected outwardly and upwardly, as shown by the dot-and-dash line 31 following the well known principle that the angle of reflection is equal to the angle of incidence. However, with the sub-reflector raised into place, the ray of light will strike the same at the point 32 and will be reflected downwardly in the direction shown by the line 33. The ray of light

illustrated by the line 34 will strike the sub-reflector at the point 36 and be reflected outwardly in the direction of the line 37.

The backward ray of light along the line 38 striking the lower reflective surface 39 at the point 41 will be reflected outwardly in the direction of the line 42 which will, in connection with the rays from the main reflector 6, give a long forward beam of light.

Figure 3 illustrates brackets 43 which may be placed between the upper edge of the sub-reflector and the concentric portion 39 of the main reflector in order that the sub-reflector may be kept in true position and not moved into or out of relation with the main reflector by reason of vibrations.

In Figure 4, supports 46 have been provided to take the place of the brackets 43 by cutting a portion of the sub-reflector and bending the same outward so that the outer ends thereof will rest against the portion 39 and may be, if desired, secured thereto.

In practice, it has been found that the reflector gives a long forward beam of light, also a downward light, and the light spreads 25 to both sides at a point very close to a line drawn across the front of the reflector.

Of course, the reflector herein illustrated may be modified in various ways without departing from the invention herein set forth 30 and hereafter claimed.

The invention is hereby claimed as follows.
I claim:—

A reflector for headlights comprising a paraboloidal body having the major portion 35 of its lower half cut along curved side lines and an upper arcuate line to form a deflector, said deflector having its upper portion pressed forward while retaining its original contour, and the peripheral edge thereof integral with said body.

In testimony whereof I have signed my name to this specification.

SEYMOUR SUITS.
